UNITED STATES PATENT OFFICE

2,329,853

OVEN FLUE DEFLECTOR FOR GAS RANGES

Harold H. Ring, Rockford, Ill., assignor to Geo. D. Roper Corporation, Rockford, Ill., a corporation of Illinois

Application November 2, 1940, Serial No. 363,971

8 Claims. (Cl. 98—121)

This invention relates to an improved oven flue deflector for domestic gas ranges.

In a gas range, the flue for conducting the products of combustion upwardly from the oven compartment requires a deflector on its upper end for directing the escaping products forwardly over the cooking top, away from the wall behind the range, and, inasmuch as this deflector is one of the most conspicuous parts of the range, it is very important that, besides being efficient and serviceable, it be of attractive appearance. It is, therefore, the principal object of my invention to provide a multiple louvered flue deflector in which the parallel louvers of graduated height, lowest in front and highest in rear, give not only the desired efficiency of operation, but also present a neat and attractive appearance.

Another object of my invention is to provide a flue deflector having parts all or most of which may be stamped from sheet metal and assembled together in a relatively few simple operations, so that the device is available at a reasonably low cost.

Still another object of my invention is the provision of a flue deflector which involves a minimum number of simple stamped sheet metal parts, and which, when assembled, is designed to be easily mounted on a flue without the addition of other parts to secure it thereon.

In the accompanying drawing:

Fig. 1 is a perspective view of the flue deflector as an assembled part on the support for the condiment set and timer, adapted to be mounted on the back rail of a domestic gas range;

Fig. 2 is a face view of a stamped and partially formed sheet metal blank from which the main body part of the deflector is formed;

Fig. 3 is a face view of the middle louver;

Fig. 4 is a plan view of the flue deflector in assembled form, ready for application to the flue;

Fig. 5 is a vertical section on the line 5—5 of Fig. 1;

Fig. 6 is a vertical section on the line 6—6 of Fig. 4;

Fig. 7 is a vertical sectional detail on the line 7—7 of Fig. 5, and

Fig. 8 is a similar sectional detail but showing another construction.

Similar reference numerals are applied to corresponding parts throughout the views.

The flue 10, with which my invention is concerned, it must be understood extends upwardly from the oven or ovens to exhaust products of combustion therefrom, the flue extending vertically in the rear portion of the range, with its up-

per end portion disposed behind the back rail. Only the extreme upper end portion of the flue is shown in Fig. 5, namely, the portion extending above the back rail, a portion of which is indicated at 9, on top of which the assembly appearing in Fig. 1 is mounted. The extreme upper end portion of the flue 10 is enclosed in a jacket 11, which serves also to space the two plates 12 and 13. The latter is adapted to rest on top of and be secured to the back rail of the range with the plate 12 and spacing jacket 11, as by through-bolts (not shown) extending vertically inside the jacket from the plugs 12a downwardly through the top of the back rail and receiving wing nuts on their lower ends, under the top wall of the back rail. The plate 12 forms a convenient shelf for support of the timer 15 and condiment shakers 16. A one-piece bent wire retaining rail 17 fits in holes in the upper plate 12 and has its depending end portion 17a entered through a hole in the lower plate 13 and suitably secured in place from beneath the latter. The upper plate 12, as indicated at 14 in Figs. 5 and 7 has an opening defined by a downwardly bent flange, into which the end of the flue 10 projects, and it is over this opening that the frame 18 of the flue deflector of my invention is mounted on the upper plate 12, in register with the end of the flue 10. The parts 11, 12 and 13 are all preferably porcelain enamelled to match the porcelain enameled back rail 9. However, the frame 18 and the rest of the flue deflector is preferably of aluminum to avoid corrosion.

The frame 18 consists of a rectangular-shaped piece of sheet metal formed to provide an integral outer, downwardly directed circumferential flange 19 to rest upon the plate 12 in outwardly spaced relation to the upper end of the flue 10. As illustrated in Fig. 2, the blank for frame 18 is punched to provide the longitudinal opening 20 having identical forked end portions defining inwardly extending lugs 21 and 22. Slots 23 and 24 are also provided in the opposite ends of the blank for the reception of lugs for support of a middle louver 25. The portions 26a and 27a of the partially formed blank shown in Fig. 2 are subsequently bent upwardly to form a larger rear louver 26 and a smaller front louver 27, as shown in Figs. 4—6, the two louvers being parallel and of substantially the same length and inclined forwardly at the same angle, as clearly shown in the drawing.

The middle louver 25 is stamped from sheet metal to the form shown in Fig. 3, its opposite lower corners being cut to form integral down-

wardly projecting lugs 29 and 31. A slot 32 is provided in the middle for the reception of a lug on a brace 33, as will be hereinafter described. Louver 25 is assembled on frame 18 by entering lugs 29 and 31 into related slots 23 and 24 and bending over the ends of the lugs. The slots 23 and 24 are long enough, as shown in Fig. 5, so that the lower edges of the louver enter the inner ends of the slots which are in the downwardly bent lug portions 21 and 22 and therefore in a plane at right angles to the outer ends of the slots, through which the ends of the louver with the lugs 29 and 31 thereon are entered. Thus, the slots 23 and 24 support the lower portion of the louver 25 in a vertical plane in addition to providing a convenient means for connecting the parts. The louver 25 is bent on a longitudinal axis 34 so that its upper portion is pitched forwardly in a parallel relation to louvers 26 and 27. The louver 25 reaches a medium height between that of the narrower front louver 27 and the wider rear louver 26, as shown in Figs. 5 and 6. In that way there is less obstruction to forward flow of gases deflected by the louvers 25 and 26, and at the same time the unit presents a neater and more attractive appearance. The middle louver 25, which, by the way, serves to locate the unit against rotary displacement relative to the flue 10 by engagement in notches 10a provided in opposite sides of the flue 10 at the upper end thereof, does not obstruct escape of gases from the flue, because its lower portion is disposed in a vertical plane, edgewise to the stream. Mitered upper corners 35 of the louver 25 are of substantially the same slope as the upper corners 36 and 37 of louvers 26 and 27, thereby giving a neat appearance.

The louvers 25, 26 and 27 are reinforced and held in spaced parallel relation at their middle portions by the transverse stamped sheet metal brace 33 secured in place, in part, by a lug 38 on its rear lower corner that enters a slot 39 in the flange 19 and by a lug 40 integral with brace 33 that is bent out of the plane of the brace to enter the slot 32 in louver 25 and thereafter straightened. The brace has a V-slot 41 provided therein to receive the louver 25. The lug 40 is on one side of the upper end of the slot 41. The front and rear edges 42 and 43 of the brace are cut so that the brace fits in the frame 18 between the front and rear louvers 27 and 26 in the manner shown in Fig. 6.

As shown in Fig. 7, the lugs 21 and 22 on opposite ends of the frame 18 are bent downwardly and inserted between the wall of the flue 10 and the downwardly projecting flange 14 on the plate 12. The deflector is then secured in place over the flue 10 on plate 12 by bending the lower ends of the lugs 21 and 22 outwardly at right angles under the lower edge of the flange 14, as indicated at 44.

In Fig. 8, there is illustrated a modified or alternative construction in which the lugs 21 and 22 of the previously described construction are eliminated from the frame 18a, the latter being, however, otherwise of the same construction as the frame 18 and having louvers 25 and 27 formed integral therewith, and also providing support for a middle louver 25. The section, Fig. 8, is taken approximately in the same plane and looking in the same direction as Fig. 7. Each end of the frame carries a pin 45 projecting vertically downwardly therefrom and arranged to be entered with a tight friction fit in a ferrule 46 mounted in a hole 47 provided therefor

in a plate 12a. The latter corresponds in other respects to the upper plate 12 of the other construction. The ferrules 46 have outwardly struck eyebrow projections 48 which when the ferrules 5 are inserted in the holes 47 are forced inwardly and subsequently spring outwardly when the ferrules 10 are moved home with their outwardly flanged upper ends 49 resting on top of the plate 12a. In that way, the ferrules are permanently secured in place. The lower ends of the ferrules are annularly beaded, as indicated at 50, for a tight friction fit on the pins 45, the ferrules, however, being thin walled and having sufficient give to enable fairly easy entry of the 15 pins, especially when the lower ends are tapered, as indicated at 51, to facilitate entry and make it easier to spread the beaded lower ends of the ferrules to the required extent.

It is believed the foregoing description conveys a good understanding of the objects and advantages of my invention. The appended claims have been drawn with a view to covering all legitimate modifications and adaptations.

1. I claim:

25 1. A louver unit comprising a one-piece sheet metal body member having an elongated opening provided therein, opposite longer sides of the opening defining edges of louver portions, and separate louvers formed by said portions bent out of the plane of said body on lines in spaced parallel relation to said edges and substantially parallel to one another, one of said louvers being of a relatively narrow but substantially uniform width from end to end and the other of said 30 louvers being of a relatively wide but substantially uniform width from end to end, the two louvers projecting from said body in substantially parallel relation to one another.

35 2. A louver unit comprising a one-piece sheet metal body member having an elongated opening provided therein, opposite sides of the opening defining edges of louver portions, and louvers formed by said portions bent out of the plane of said body on lines in spaced parallel relation to said edges and substantially parallel to one another, one of said louvers being of a relatively narrow but substantially uniform width from end to end and the other of said louvers being of a relatively wide but substantially uniform width from end to end, the two louvers projecting from said body in substantially parallel relation to one another, and a separate intermediate louver mounted on said body substantially midway between the first mentioned louvers and in substantially parallel relation thereto, said intermediate louver being of a medium but substantially uniform width from end to end.

40 3. A louver unit comprising a sheet metal body having an elongated slot provided therein that is forked at opposite ends, the portions on opposite sides of said slot being suitable for louvers and the generally V-shaped portions at opposite ends of said slot being suitable for attaching lugs, louvers on said body formed by said first 45 named portions bent out of the plane of said body along lines substantially parallel to the edges of said portions forming the opposite sides of the longitudinal slot, and lugs on said body at the opposite ends of said slot formed by said V-shaped portions bent from the plane of said body in the opposite direction relative to said louvers to engage with supporting means and thereby secure the unit in fixed position.

4. A louver unit comprising a sheet metal body

having an elongated slot provided therein that is forked at opposite ends, the portions on the opposite longer sides of said slot being suitable for louvers and the generally V-shaped portions at opposite ends of said slot being suitable for attaching lugs, louvers on said body formed by said first named portions bent out of the plane of said body along lines substantially parallel to the edges of said portions forming the opposite longer sides of the longitudinal slot, and lugs on said body at the opposite ends of said slot formed by said V-shaped portions bent from the plane of said body in the opposite direction relative to said louvers to engage with supporting means and thereby secure the unit in fixed position, one of the louvers being of relatively narrow but uniform width from end to end and the other of said louvers being of relatively wide but uniform width from end to end, and the two louvers being bent at substantially the same acute angle relative to the plane of said body and so as to project from said body in the same direction.

5. A louver unit comprising a sheet metal body having an elongated slot provided therein that is forked at opposite ends, the portions on opposite sides of said slot being suitable for louvers and the generally V-shaped portions at opposite ends of said slot being suitable for attaching lugs, louvers on said body formed by said first named portions bent out of the plane of said body along lines substantially parallel to the edges of said portions forming the opposite sides of the longitudinal slot, and lugs on said body at the opposite ends of said slot formed by said V-shaped portions bent from the plane of said body in the opposite direction relative to said louvers, the body having two other slots provided therein adjacent said V-shaped end portions, and another louver disposed between the first mentioned louvers and having means on the ends thereof entered in said last named slots for support of said louver on said body.

6. A louver unit comprising a sheet metal body having an elongated slot provided therein that is forked at opposite ends, the portions on opposite sides of said slot being suitable for louvers and the generally V-shaped portions at opposite ends of said slot being suitable for attaching lugs, louvers on said body formed by said first named portions bent out of the plane of said body along lines substantially parallel to the edges of said portions forming the opposite sides of the longitudinal slot, and lugs on said body at the oppo-

site ends of said slot formed by said V-shaped portions bent from the plane of said body in the opposite direction relative to said louvers, the body having two other slots provided therein in alignment with one another and in substantially parallel relation to the first named slot, the last named slots being elongated so that the inner end portions thereof are included in the V-shaped lug portions bent from said body, and another louver disposed between the first mentioned louvers with the opposite ends thereof entered in said last named slots for rigid support of the louver on said body, said louver also having means on the ends thereof for detachably securing the same against displacement from said slots.

7. In combination, a support having an opening provided therein, a conduit having a discharge end portion extending into said opening, 20 and a louver unit comprising a sheet metal body member mounted on said support in register with the end of said conduit and having louver portions bent outwardly from the plane of said body adjacent opposite sides of the conduit and extending at angles to the body in the same direction for deflecting a flow discharged from said conduit in a predetermined direction relative to said conduit and support, and another louver comprising a supporting portion detachably 25 mounted on said body and extending across the middle of said conduit in a plane parallel with the axis thereof, and a deflecting portion bent in angular relation to the supporting portion outside said body and in the same direction as the first mentioned louvers.

8. A louver unit comprising a one-piece sheet metal body member having an elongated opening provided therein, opposite sides of the opening defining edges of louver portions, and louvers formed by said portions bent out of the plane of said body on lines in spaced parallel relation to said edges and substantially parallel to one another, another intermediate louver having means for securing the opposite end portions thereof to said body for support of the louver in substantially parallel relation to the first mentioned louvers, and a transverse brace intermediate the ends of said last mentioned louver secured to said louver and having abutment at its opposite ends 40 with the first mentioned louvers to hold the intermediate louver in fixed spaced relation to the first mentioned louvers.

HAROLD H. RING.
